Carrier Corporation, Syracuse, N. Y., a corpora-
tion of Delaware

Original application August 12, 1939, Serial No.
289,749. Divided and this application July 7,
1942, Serial No. 450,055

3 Claims. (Cl. 257—6)

This invention relates to indicating control devices and is a division of application Serial No. 289,749, filed August 12, 1939.

The general object of the invention is to provide an indicating device for a control valve serving an air conditioning unit, arranged to indicate how conditioning fluid may be increased or decreased in flow to the unit, although the fluid may be hot or cold under different operating conditions.

A feature of the invention resides in the provision of a plurality of indicating symbols on a plate adapted to reflect the flow of heated or cooled fluid through a valve serving an air conditioning unit, said symbols serving to instruct an operator how to obtain a colder or warmer condition regardless of the character of the fluid being circulated to the unit.

A further feature provides for the use of a plurality of circuits for circulating hot or cold fluid to a valve serving a heat exchanger unit whereby a positive guide will be afforded to an operator desiring to vary the heating or cooling effect of the unit, said valve requiring reverse operation when cooling fluid employed to that required when heating fluid is employed for obtaining equivalent compensation for changes in load affecting the unit.

These and other features will be apparent from the following description of the invention to be read in connection with the accompanying drawing in which:

Figs. 1, 2, 3, and 4 illustrate a valve and indicator mechanism for carrying out the invention.

Referring more particularly to Fig. 1, the numeral 103a designates a valve capable of automatically modulating the heating or cooling effect of a coil 99 of a local air conditioning unit. The control element which is preferably used in conjunction with the valve comprises a length of finned tubing 119 of the type commonly used in the construction of heat exchangers. One end of the tube is sealed and the other end connects with a pressure tube 120 which extends within the housing 121 of the valve 103a. The control element 119 is filled with a volatile fluid adapted to expand and contract with changes in temperature, such as ether, and the control element 119 is placed within and in the path of air in-taken within the unit containing heat exchanger coil 99 so that the control element reflects the temperature within the enclosure served by the unit. The control element is preferably shielded in any desired manner from the heating or cool-

ing effect of the coil 99 so as to insure more accurate control.

Through the top cap 122 of the valve there extends adjustable rod 123 bearing against a flanged disc or the like 124. The rod 123 is provided with a control handle 122 for use in adjusting the setting of the valve.

The flange 125 is secured in a gas-tight manner to the upper extremity of an expansible bellows 126, the lower extremity of the bellows being secured in a fluid-tight manner to a disc 128. The pressure tube 120 leads from the interior of the thermal element 119 to the interior of the bellows 126 so that as the temperature affecting the control element 119 is varied, the bellows 126 is caused correspondingly to expand and contract. A stud 127 extends within the interior of the bellows to decrease the free volume in the bellows, as this insures a more prompt and sensitive operation of the valve. The disc 128 is connected to a rod 128 extending downwardly therefrom and bearing a flange 129 at its lower extremity. The rod 128 extends within a cup-shaped member 130 and the flange 129 provides for retention of the rod 128 within the member 130 so that as the rod 128 is raised the member 130 will be raised correspondingly. A spring 131, extending between the bottom of disc 128 and the top of member 130, tends to maintain maximum separation of these two elements. The lower portion of member 130 carries a disc 131a to which there is connected, in a fluid-tight manner, a sealing bellows 132, and also a rod 133 extending through a plate 134 to which the bellows 132 is connected. Thus, the operating fluid of the thermal element is prevented from escaping within the valve and also the water or brine controlled by the valve is effectively prevented from escaping within the valve.

The rod 133 bears downwardly upon a lever 135 pivoted at 136. The free end of the lever 135 bears downwardly upon a lever 137, pivoted at 138, at a point proximate the fulcrum 138. The lever 137 is adapted to actuate the valve stem 139 which is operably connected through a star-shaped guide 140 to a valve closure member 141, comprising a pair of oppositely arranged faces 142. The arrangement of levers 135 and 137 is employed for the purpose of multiplying the motion of the primary control rod. Thus for a given movement of the valve rod 133 the corresponding movement of valve rod 139 may be four or five times as great. This amplification makes for increased sensitivity and refinement of control

and makes it possible to maintain within very close limits the desired temperature in the conditioned enclosure.

The valve seat serving the upper face 142 is formed in a partition plate 143 provided between the upper connection 104 and the center connection 105 of the valve. The seat 144, cooperating with the lower face 142 of the valve member 141, is disposed between the central connection 105 and the bottom connection 106 of the valve. Spring 145, operating on valve guide 146, biases the valve in an upward direction.

Under summer operating conditions, or whenever cooling is required, a temperature higher than that desired requires an increased flow of cooling medium through the valve. Under winter operating conditions, however, a temperature higher than normal calls for a decreased rate of flow of heating medium through the coil.

Lines 63 and 67 connect to and lead from central station sources of heating and cooling fluid, the arrows indicating the direction of flow under summer and winter operating conditions.

Under summer operating conditions, cooling medium enters the valve through the central connection 105. Assuming a demand for cooling to exist, the high temperature affecting the control element 119 will cause depression of the valve 141 and thus some of the liquid entering the valve at connection 105 will flow upwardly and out of the valve through 104 and through line 147 to the heat exchange coil 99. The conditioning medium passing from the coil is routed through line 148 to junction 149 and then passes through pipe 150, containing check valve 150a, to line 67 and is thus returned from the local unit. The portion of the conditioning medium supplied to the valve which is not so routed, passes downwardly in the valve past the valve seat 144 and is discharged through connection 106 to line 151 through which it passes to junction 149, where this fluid is joined with the fluid discharged from the conditioning coil 99 and is returned therewith to the line 67. As more conditioning is required under summer operating conditions, more cold liquid is circulated through the conditioning coil 99 and less is bypassed through 106, and as less conditioning is required less cold liquid will be supplied to the coil 99 and more will be bypassed through 106.

Under winter operating conditions reverse operation occurs, and in this case an increased temperature affecting the thermal control element 119 results in decreased supply of conditioning medium, which is then at a relatively high temperature, to the conditioning coil. Under winter operating conditions, conditioning medium is supplied through line 67 and passes through the branch line 152 containing check valve 152a, to junction 153. Part of the conditioning medium travels through the pipe 147 and enters the valve at connection 104 and passes downwardly therein and is discharged from the valve through connection 105. The other portion of the conditioning fluid passes from the junction 153 to the conditioning coil 99, is discharged therefrom through line 148 and through connection 151, and enters the valve at 106 and is discharged therefrom through central opening 105 together with the fluid which was bypassed through connection 147. As the temperature affecting the thermal control element 119 rises, the valve 141 will be lowered and hence more of the conditioning fluid will be bypassed from 104 to 105, and correspondingly less of the conditioning fluid will pass through the coil 99 and the lower portion of the

valve from 106 to 105. Conversely, if the temperature is lower than desired, more of the heating fluid will be routed through the conditioning coil and a lesser quantity will be bypassed.

- 5 When the valve controlling the action of the heat exchange coil 99 is controlled manually, there is no necessity for reversing the flow of the conditioning medium through the pipes 63 and 67 as in the case of automatic control in the manner just described, since an operator can readily turn the valve in either direction as required to bring about the desired change in the conditioning action. Thus, under summer operating conditions, when the local unit is supplied with cooling medium, if the temperature in the enclosure served by the unit is too high the operator will depress the valve 141 so as to permit increased flow of cooling medium from opening 105 to opening 104 serving the pipe 108, which delivers conditioning medium to the coil 99; and if the temperature is too low the operator will adjust the valve to raise the valve member 141 so that a lesser quantity of cooling medium flows through the conditioning coil 99. Under winter operating conditions, when heating medium is supplied to the conditioning unit, the operation is merely reversed. Thus, when the temperature in the enclosure is too high, the operator will raise the valve 141 to diminish the supply of heating medium to the coil 99 through the pipe 108, and if the conditioned enclosure is too cold, the valve 141 will be depressed to permit a greater supply of conditioning medium to the coil 99 through the connection 106.
- 10 35 During intermediate seasons, however, certain operating difficulties tend to arise. Thus, under certain conditions some of the zones of a conditioned enclosure may require heating while others require cooling. Under such circumstances an operator seeking manually to adjust the valve might have some difficulty in determining whether the unit was being supplied with hot or cold water. Thus, if the operator put his hand over the air outlet grille of a unit supplied with hot water, he might experience a sensation of cooling arising from the relatively low dewpoint of the air and its relatively high velocity, although the delivered air might actually be at a higher temperature than the air in the room.
- 15 40 45 50 55 60 65 The sensation of cooling might lead the operator to believe that the unit was being supplied with cool water and, feeling too warm, he would naturally open the valve wider. If in fact the unit was being supplied with warm water, such increased opening of the valve would naturally aggravate his discomfort. Thus, there is indicated a need for a device which will positively indicate to the operator the direction in which the valve should be adjusted to produce a desired change, so that under both summer and winter operating conditions, and regardless of whether the unit is being supplied with warm water or cold water, the operator will at all times be enabled to make the required adjustment promptly and without experimentation.

To this end there is preferably provided an arrangement such as illustrated in Figs. 2-4, which automatically indicates the direction in which the valve should be turned to provide for desired regulation of the room temperature, regardless of whether the unit is being supplied with hot water or cold water.

As illustrated, a thermal bulb 154 is placed in heat exchange relation with the water supply

pipe 107. A pressure control line 155 leading from the thermal bulb 154 communicates with the interior of an expansible bellows 156. The expansible bellows 156 carries a slide plate 157 bearing suitable indicia indicated at 158. The slide plate 157 may be supported by suitable flanges or the like 159 and the plate 157 is mounted just beneath the top 160 of the conditioner casing, preferably at an end thereof. In the top of the conditioner casing are provided a plurality of apertures, one of these being designated 161 and the other 162. When the unit 53 is being supplied with cold water, the bellows 156 will be relatively contracted and the marking "W" or "Warmer" or the like may then be visible through the aperture 161 while the marking "C" or "Colder" or the like may be visible through the aperture 162. Thus, under summer operating conditions, or when cold water is being supplied to the unit, the operator will turn the valve handle 112 in a clockwise direction as seen in Fig. 7 to increase the cooling effect, and in a counter-clockwise direction as seen in Fig. 7 to decrease the cooling effect. Under winter operating conditions, or when heating medium is being supplied to the local unit 53, the bellows 156 will be caused to expand. This will move the slide 157 and the indicia visible through the apertures 160 and 162 will therefore be reversed. Therefore, if an operator under winter operating conditions feels too warm the valve handle 112 will then be turned in a counter-clockwise direction as seen in Fig. 3 to increase the conditioning effect, and if he feels too cool the valve handle will be turned in a clockwise direction as seen in Fig. 3. As will be understood, the valve handle is so arranged that adjustment of the handle in accordance with the position of slide 157 will effect the required adjustment of valve closure member 141.

I claim:

1. In a valve and fluid circuiting arrangement, a heat exchanger, a manually operated valve device, fluid supply and return lines, means for circulating cooled fluid through said lines to said valve device and exchanger under summer operating conditions, means for circulating heated fluid through said lines to said valve device and exchanger under winter operating conditions, a thermal bulb positioned in contact with said fluid supply line, an expansible bellows and pressure control line connected to said bulb, a slide plate attached to said bellows, a casing, said plate being mounted in slidable relation to said casing, a pair of apertures in said casing adjacent said valve device, indicating symbols on said plate, said symbols being arranged with respect to said apertures so that when cooled fluid is circulated through said valve device the indicating symbols exposed to view through the apertures will be in a certain order from left to right whereas when heated fluid is circulated through the valve device the symbols will be exposed to view in reverse.

2. In a valve and fluid circuiting arrangement, a hot and cold fluid metering valve, a heat exchanger, a plurality of conduits connecting said valve and exchanger, supply and return lines, means for circulating cooled fluid through said lines, valve and conduits to serve the exchanger in one circuit arrangement, means for circulating heated fluid through said lines, valve and conduits to serve the exchanger in another circuit arrangement, means connected to said valve for reflecting the temperature of fluid passing therethrough, an actuating device under control of said last mentioned means, a marker plate adapted to be moved by said device, a pair of symbols on said plate for use under summer operating conditions when cooled fluid is circulated, another pair of symbols on said device for use under winter operating conditions when heated fluid is circulated, a stationary plate in superposed position with respect to said symbols, a pair of apertures in said plate, and a single control device for regulating the flow of heated or cooled fluid through the valve, said symbols indicating how said control device should be operated to obtain desired compensation for differences in load affecting an enclosure served by the heat exchanger.
3. In a valve and fluid heating arrangement, a hot and cold fluid metering valve, a heat exchanger, a plurality of conduits connecting said valve and exchanger, supply and return lines, means for circulating cooling fluid through said lines, valve and conduits to serve the exchanger under summer operating conditions, means for circulating heating fluid through said lines, valve and conduits to serve the exchanger under winter operating conditions, means for reflecting the temperature of fluid passing through the valve, an actuating device connected to said last mentioned means and adapted to assume different positions depending upon the temperature of the fluid being circulated, a marker-plate attached to said device, a pair of symbols on said plate grouped together, another pair of symbols on said plate grouped together, a stationary plate in superposed position with respect to said symbols, a pair of apertures in said stationary plate, said apertures being positioned in such manner that one symbol of each pair of symbols is exposed to view under summer operating conditions, the other symbol of each pair of symbols being exposed to view under winter operating conditions, and a single rotatable control device for regulating the flow of heating or cooling fluid through the valve, the symbols being caused to indicate that the control device should be turned in a clockwise direction to obtain greater cooling effect under summer operating conditions and greater heating effect under winter operating conditions.

WILLIS H. CARRIER.
